[57] CLAIM

The ornamental design for a container for holding fishing tackle accessories, as shown and described.

DESCRIPTION

FIG. 1 is a top right front perspective view of a container for holding fishing tackle accessories showing our new design;

FIG. 2 is a top plan view thereof;

FIG. 3 is an inverse front elevational view thereof; the rear elevational view being a mirror image;

FIG. 4 is a right side elevational view thereof; the left side elevational view being a mirror image; and,

FIG. 5 is a bottom plan view thereof.

*FIG. 1**FIG. 2**FIG. 3**FIG. 4**FIG. 5*
